METHOD OF RECLAIMING MECHANICAL
KNITTING NEEDLES

George L. Hofmeister, Brooklyn, N. Y.

Application September 27, 1948, Serial No. 51,407

3 Claims. (Cl. 163—5)

1

This invention relates to a method of and means for reclaiming damaged steel or alloy needles which have been employed in woolen knitting machines.

Broadly the invention contemplates a method of reclaiming mechanical knitting needles each having a damaged end and an undamaged end in which the needles are assembled in pairs, the damaged ends are cut off and the undamaged ends are welded together to form reclaimed needles substantially as good as new needles.

More particularly the invention comprises a step method of reclaiming mechanical knitting needles each having a damaged end and an undamaged end in which the needles are manually assembled in pairs and in the order named engaging them in gripping or holding mechanism, mechanically carrying them progressively through the steps of mechanically aligning the pairs of needles, cutting off the damaged ends, bringing the pairs of remaining undamaged ends into juxtaposition with each other, welding them together, annealing and tempering the welded portions, grinding or dressing of burrs resulting from the welding, and polishing the welded portions, and means for performing the successive steps of the method of the invention.

An object of the invention is to provide an effective method of reclaiming damaged mechanical knitting needles for reuse.

Another object of the invention is to provide mechanical means for progressively performing the several steps of the reclaiming method in an orderly and precisely uniform manner.

These and other objects and novel features of the invention will be understood by referring to the following detailed description together with the figures of the accompanying drawings illustrating preferred embodiments of the invention and in which drawings:

Fig. 1 is a diagrammatical view in side elevation of the means of the invention in which the steps of the method are indicated at progressively numbered stations.

Fig. 1A is a schematical plan view of a series of mechanical knitting needles projected to illustrate the steps in the method of the invention from the manual insertion in the holding means through the welding step.

Fig. 2 is an enlarged view in elevation of two undamaged portions of two needles each having had a damaged end, two undamaged portions immediately after welding them together and a completely reclaimed needle.

Fig. 3 is a plan view of a single platform as-

2

sembly of a platform chain upon which the invention is practiced illustrating two needles each having a damaged end engaged in the holding mechanism.

5 Fig. 4 is a view taken on the line 4—4 of Fig. 3.
Fig. 5 is a view taken on the line 5—5 of Fig. 3.

Fig. 6 is a fragmentary view in plan of a platform assembly and a needle holding mechanism having a portion cut away, and showing a needle and a set of conventional cutting blades dotted in.

10 Fig. 7 is a view taken on the line 7—7 of Fig. 6, illustrating in dotted lines a cam for depressing the electrodes and a mercury container for completing an electrical connection.

15 Fig. 8 is a view in elevation illustrating in dotted lines a set of conventional cutting blades for shearing the needles.

Fig. 9 is a view taken on line 9—9 of Fig. 6 illustrating certain of the elements in full view.

20 Fig. 10 is a view taken on line 10—10 of Fig. 9 showing an anchor screw in full view.

Fig. 11 is a fragmentary view in end elevation of a platform assembly taken at the end opposite of the view of Fig. 6.

25 Referring now to the drawings:

In the step performed at station numbered 1 in Fig. 1 two woolen knitting machine needles 29 and 31, each of which has a damaged end and an undamaged end are manually inserted by the undamaged ends into needle holders 30 and 31, which are shown more in detail in Fig. 3, Fig. 4, and Fig. 5.

In the step which is performed at station 1 shown in Fig. 1 an overhead trip mechanism of

35 a conventional character e. g. of the rocker-arm type having a depending contact member, not shown, is provided for pressing against the inclined surfaces of trigger members 32 and 33 of the needle holders 30 and 31, which serves to de-

40 press the trigger members 32 and 33 in the direction of and against compression springs 40 and 41 and the trigger members 32 and 33 rocking upon pins 42 and 43 serve to lift bearing pins 35, 36, and 36, which are attached to the plate

45 portions 37 and 38 of the trigger members 32 and 33. Suitable adjusting nuts 44 and 45 are provided for cooperating with the threaded ends of core rods 46 and 47 whose ends opposite the threaded ends are rigidly attached to plate mem-

bers 48 and 49, for regulating the tension in compression springs 40 and 41 which bear against the return ends of yoke or housing members 50 and 51 to which U members 26 and 27 are rigidly attached respectively by set screws 28 and 29 and 55 which in turn are anchored respectively to plates

68 and 69. The threaded ends of the core rods 46 and 47 are shaped convexly and spherically so that they may rock freely in spherical concavities in the trigger members 32 and 33 against which they bear.

When the trigger members 32 and 33 are rocked upon the pins 42 and 43 the core rods 46 and 47 are moved against the compression springs 40 and 41 thus compressing them and increasing the tension, and at the same time the plates 48 and 49 are brought to bear forcibly against lock nuts 52, 52, and 53, 53, which cooperate with the threaded ends of link rods 54, 54, and 55, 55 before the movement of the trigger members 32 and 33 is complete. The movement of the trigger members 32 and 33 is completed after the plates 48 and 49 are brought to bear against the nuts 52, 52, and 53, 53 which (being attached thereto) serve to move the link rods 54, 54, and 55, 55, and whose ends opposite the threaded ends being attached to securing plates 56 and 57 serve to move the securing plates 56 and 57 slightly before the movement of the trigger members 32 and 33 is completed. The slight movement of the securing plates 56 and 57 may be adjusted by positioning the nuts 52, 52, and 53, 53, upon the cooperative ends of the link rods 54, 54, and 55, 55, so as to provide sufficient space or clearance between the securing plates 56 and 57, and the respective companion (fixed) securing plates 58 and 59 to permit the insertion of the needles 20 and 21 therebetween.

The securing plates 56 and 57 are supported by screws 60, 60 and 61, 61 from the ends of the link rods 54, 54 and 55, 55 beneath outturned portions of the skirt of the yoke or housing members 50 and 51, and which outturned portions serve as track-like supports for the link rods 54, 54, and 55, 55 and the securing plates 56 and 57. Compression springs 62, 62, and 63, 63, are mounted upon core rods 64, 64 and 65, 65, each having one end threaded and adjusting nuts 66, 66, and 67, 67, mounted thereupon, and which ends bear against the securing plates 56 and 57, the other ends being slidably mounted in holes provided in depending portions of the return ends of the yokes or housing members 50 and 51.

From the foregoing detailed description it may be seen that when the trigger members 32 and 33 are rocked upon the pins 42 and 43 the needle holders 30 and 31 are opened to receive the needles 20 and 21, and thereafter when the trigger members 32 and 33 are released the compression springs 62, 62, and 63, 63, act to press the securing plates 56 and 57 against the needles 20 and 21 and the needles against the fixed securing plates 58 and 59, thereby securing the needles laterally, and that the springs 40 and 41 act to forcibly depress the bearing pins 35, 35, and 36, 36, upon the needles 20 and 21 thereby securing them vertically against table plates 68 and 69. Moreover when the needles are manually inserted the curved ends of the hooks on the needles serve to force upwardly suitable latches 22 and 23 which are rotatably pinned to stop members 24 and 25 and which latches will drop back into place when the hook portions of the needles have cleared them to thereby secure the needles 20 and 21 longitudinally.

Table plate 69 which has the trigger member 33 mounted on it, is rigidly secured to a frame plate 70 which is cut out about the center section for lightness and to permit dropping therethrough the damaged ends of the needles when they are cut off. The table plate 68 which has the trig-

ger member 32 mounted on it is slidably secured by track strips 71 and 72 to the frame plate 70. Electrically conductive members 73 and 74 made preferably of springy plate metal or alloy capable of being depressed at a proper stage during the cycle of the method and later when released will spring back into the relative positions shown in Fig. 4, are provided with electrode members 75 and 76 which are secured thereto and whose function will be disclosed completely hereinafter.

The entire platform assembly illustrated in Fig. 3 and Fig. 4 is typical of a number of such platform assemblies which are attached together by hinges 77, 78, 79, and 80, thereby to form a continuous platform chain as illustrated in Fig. 1 which is appropriately mounted upon a frame of a frequently used type of construction consisting of structural shapes, such as angle iron, vertical and horizontal supporting members with the customary cross bracing bars secured together for rigidity, and provided with appropriate bearing members (not shown), and hexagonal or octagonal supporting members supported in said bearing members and which in turn are adapted to support and when rotated, to move the platform chain step by step in the practice of the method of the present invention.

When the functions of the first step of the method have been completed in the stage as shown at station 1 in Fig. 1 which comprises mechanically opening the needle holders 30 and 31 and manually inserting two needles 20 and 21 with their damaged ends turned inwardly as shown in Fig. 1A and thereafter releasing the overhead trip mechanism (previously described but not shown) for opening the needle holders 30 and 31 thereby permitting them to grip the needles 20 and 21, an electric motor 11 is started and acting through a system of gears in a gear box 12, a cam 13, a companion gear 14, a shaft 15, a pinion 16 and a gear 17 mounted upon a shaft 18 upon which the hexagonal supporting member 81 is also mounted, the hexagonal member 81 is caused to rotate one sixth of a turn to thereby advance the entire platform chain a distance equal to the width of one platform. While a hexagonal supporting member 81 is shown and described herein, it is to be understood that an octagonal or for that matter a circular supporting member may be employed if more suitable for a given operation.

The second step in the method which is performed at station 2 when the platform chain is advanced one platform width comprises a mechanical alignment in preparation for cutting off the damaged ends of the needles 20 and 21. The immediate invention further contemplates suitable mechanism of a conventional character for performing the aligning. The aligning itself consists mainly of regulating precisely the extent of the projection of the damaged ends of the needles 20 and 21 inwardly from the holders 30 and 31 so as to place them in exactly the proper relative location for being cut off. It is extremely important that just a sufficient amount of stock be left on the undamaged ends of the needles to compensate for that portion which is fused and lost when they are welded together so as to produce a reclaimed needle that will be of an exactly required length.

Following the aligning step the platform chain is advanced and at station 3 the damaged ends of the needles are cut off mechanically. In this step also this invention contemplates the employment of a suitable mechanism of conventional

character. Actually any conventional mechanical shears adapted for cutting the needles may be employed, e. g. one comprising two small tool steel plates preferably matched as to shape, each having a slot in one of its edges matching a slot in the other adapted to receive a needle, whose contiguous edges produce a combined twisting and shearing action upon a needle as they are rotated relative to each other when using the needle engaged in the slots as an axis. After the cutting off is performed the remaining undamaged ends of the needles are in substantially the relative position as shown for this stage in Fig. 1A.

In the next stage, i. e. at station 4, the step of bringing the inner ends of the needles into contact is accomplished by mechanically sliding the slideable table plate 68 having the needle holder 30 mounted upon it a predetermined distance toward the fixed table plate 69 having the needle holder 31 mounted upon it. In this step also the invention contemplates the employment of a suitable mechanism of conventional design for sliding the table plate 68 but a relatively simple system may be provided which is adapted to be actuated by the motor 11 so as to be timed in coordination with the movement of the platform chain as it is advanced through the several steps of the method of this invention. For example a conventional cam system actuated by the motor 11 and simultaneously with cam 13, may engage with and move a table plate 68 toward a table plate 69 at station 4, while engaging with and moving another table plate 68 away from another table plate 69 at a station X directly below station 4. The amount of movement of the table plate 68 must of necessity be accurately regulated so that uniformity of length of reclaimed needles may be attained as explained above.

In the next stage in which the step of welding the needle ends together is to be performed at station 5, guides or cams 95 and companion guides or cams situated at opposite ends of platforms (not shown) engaged the electrically conductive members 73 and 74 and electrodes 75 and 76 and the electrode points are brought into contact with mercury baths 97 and companion mercury baths situated at opposite ends of platforms (not shown) or other suitable electrical conductors (not shown) which are connected at opposite poles with a suitable electrical source (not shown). The members 73 and 74 are secured to plates 68 and 69 respectively through electrically conductive filler plates 91 and 92, and U plates 93 and 94. The securing plates 56, 51, 58 and 59 and the table plates 68 and 69 are preferably formed of electrically conductive metal or alloy and thus serve to conduct the electrical current necessary for welding together the contiguous ends of the needles 20 and 21 when in ordinary practice the current is turned on by conventional mechanically timed switching apparatus (not shown) e. g. a multiple control clocking mechanism having electrical contact points. Inasmuch as the welding operation requires only momentary contact the current is turned on and quickly off while the needle ends are held together, to thereby perform the welding. The timing in this step is coordinated with, but preferably independent of the movement of the platform chain. The frame plate 70 is preferably formed of non-conductive material.

In the next stage the step of annealing the weld is performed at station 6. The welded portion of the needle which still is secured in the needle holders 30 and 31 and in contact with members 75

56, 57, 58, 59, 68, and 69 which are electrically connected to opposite poles of an electrical source (not shown) as previously explained is subjected to timed heating as previously described in connection with the welding step, after the platform chain is brought to a stop in this stage. The temperature to which the needle is subjected and the length of time of the treatment in this stage may be regulated by the multiple control mechanically timed switching apparatus (not shown) previously described in accordance with good practice. The timing of the heat treatment in this step is preferably coordinated with but independent of the timing of step movements of the platform chain.

In the next stage the step of tempering is performed at station 7. In this step also the welded portion of the needle which still is secured in the needle holders 30 and 31 is again subjected to timed heating in a manner such as described in the preceding stage after the platform chain is brought to a stop. Here also the heating is timed by multiple control means (not shown). Ordinarily the tempering step may require somewhat higher temperature and shorter time interval than the annealing step requires and in this step also the timing is preferably coordinated with the movement of the platform chains, but independent thereof.

30 In one sequence of steps which may be selected in the practice of the invention immediately the platform chain is advanced a step and brought to a stop the electrical current may be switched on to perform the heating in the tempering step and then switched off and as the current is switched off in this step it may be switched on in the annealing step, and immediately the proper heat soaking in that step is completed the current may be switched off and immediately thereafter be switched on momentarily and then off in the welding stage. The sequence as related is set forth for the reason that since the higher temperature is required for the tempering step it will take a somewhat longer time to quench and cool the needle, while in the annealing step a lower temperature but somewhat longer soaking time is required and the needle may be transferred immediately from the heat soaking in the annealing step to the tempering step and preferably without the necessity of allowing any time for cooling. Moreover since the welding step is accomplished so rapidly and at the highest temperature, and after which the needle is to be subjected at once to annealing the move from the welding to the annealing step may be made at once the welding is completed. Further, it is to be seen that time for proper treatment in the tempering step is provided during the performance of the successive annealing and welding. 60 An added advantage of course is that the electrical load requirements are kept to a minimum by performing the steps separately and successively as described.

The foregoing description and the order of steps as set forth therein is given for the particular purpose of clarifying the method of the invention and it is pointed out now that no limitation to the method is intended by the order set forth. For example it may be perceived readily that in the several steps described those of annealing and tempering require the longest time interval while all of the other steps may be accomplished in relatively short time. Therefore the step movements of the entire platform chain may be speeded up over the sequence foregoingly de-

scribed by performing the annealing and tempering steps each simultaneously and continuously throughout two or more movements of the platform chain, thereby to double or more the actual rate of reclamation or output in the practice of the invention. To further exemplify, the actual time required to perform the annealing or tempering step may be as long as six seconds while all of the other steps may be performed in one second each. Thus if following the sequence as 10 foregoingly described in detail in which the performance of each step was described as being accomplished completely in one step movement of the platform chain the output rate would be one needle reclaimed each six seconds. On the 15 other hand if the annealing step and the tempering step were to be accomplished in two or three step movements of the platform chain then the output rate would become one needle reclaimed each three seconds or each two seconds as the 20 case may be.

It has been stated previously herein that following the cutting step the slideable plate 68 was moved mechanically toward the fixed plate 69 so as to bring the needle ends into contact. Following the ejection step which is performed at station 8 as shown in Fig. 1 where the needle holders 30 and 31 are mechanically tripped (by means similar to those previously described but not shown) to release the needles the platforms of the platform chain are continuously moved step by step and each is returned finally to station 1 to begin a new cycle. During the return movement the slideable plate 68 is preferably moved away from the fixed plate 69 so as to prepare the platform assembly for receiving other damaged needles in the initial stage of the processing according to the invention. Such movement of the plate 68 is preferably performed mechanically (by means previously described but not shown) at a point X approximately opposite vertically where another slideable plate 68 of another platform assembly at station 4 is moved toward another fixed plate 69 as previously described. Such point for the mechanical return movement of the slideable plate 68 is selected so that the same cam system (not shown) which is employed to move the upper slideable plate 68 in one direction may be employed to move the lower slideable plate 68 in a reverse direction.

Following the tempering step at station 7 of Fig. 1 the platform assemblies of the platform chain are moved by steps around the hexagonal (or octagonal or circular) support 82 and at station 8 the needles are ejected mechanically by means (similar to those previously described but not shown) adapted to open the trigger members 32 and 33 and eject the needles which thereafter are delivered to a grinding mechanism indicated at station 9, where the burr produced by the welding is removed. The grinding mechanism may be of a conventional type resembling a wood working planing machine which employs an emery wheel instead of a rotary cutter over which the needles are passed manually first one side and then another until all burrs are dressed off.

From the grinding step the needles are delivered to a polishing mechanism indicated at

station 10 where the needles are subjected to a polishing in the area of the weld on a machine of a kind similar to or on the same machine as the grinding operation is performed in which a polishing or buffing element is employed, so as to render them smooth and which final step has the effect of producing a reclaimed needle which has the appearance and the quality of a new needle.

From the foregoing description, the accompanying drawings and the appended claims, it will become obvious to one skilled in the art, that other embodiments and slight variations in the method disclosed may be employed without departing from the spirit and the scope of the invention.

I claim:

1. The method of reclaiming mechanical knitting needles each having a damaged end and an undamaged end which comprises assembling the damaged needles and arranging them in pairs, placing the needles manually in holding means, and thereafter aligning the needles with appropriate relationship to each other preparatory to cutting of the damaged ends, cutting off the damaged ends, bringing the ends of the remaining portions of the needles into contact with each other and welding said ends together to thereby form a new undamaged needle.

2. The method of reclaiming mechanical knitting needles each having a damaged end and an undamaged end which comprises assembling the damaged needles and arranging them in pairs, placing the needles manually in holding means, and thereafter aligning the needles with appropriate relationship to each other preparatory to cutting of the damaged ends, cutting off the damaged ends, bringing the ends of the remaining portions of the needles into contact with each other, welding said ends together, subjecting the welded needle to an annealing and tempering treatment to thereby form a new undamaged needle.

3. The method of reclaiming mechanical knitting needles each having a damaged end and an undamaged end which comprises assembling the damaged needles and arranging them in pairs, placing the needles manually in holding means, and thereafter aligning the needles with appropriate relationship to each other preparatory to cutting of the damaged ends, cutting off the damaged ends, bringing the ends of the remaining portions of the needles into contact with each other, welding said ends together, subjecting the welded needle to an annealing and tempering treatment, grinding and polishing the needles to thereby form a new undamaged needle suitable for immediate reuse.

GEORGE L. HOFMEISTER.
